[57] CLAIM

The ornamental design for a cathode-ray tube console,
as shown and described.

DESCRIPTION

FIG. 1 is a perspective view of the cathode-ray tube
console showing my design;

FIG. 2 is a top plan view of the cathode-ray tube con-
sole on a reduced scale;

FIG. 3 is a rear elevational view of the cathode-ray tube
console on a reduced scale; and

FIG. 4 is a side elevational view of the side opposite
that shown in FIG. 1 of the cathode-ray tube console on
a reduced scale.

FIG. 1

FIG. 2

FIG. 3

FIG. 4
